US0D1060333S

(12) **United States Design Patent** (10) Patent No.: **US D1,060,333 S**
Chen et al. (45) Date of Patent: ** Feb. 4, 2025

(54) **COMPUTER MAINFRAME**

(71) Applicant: **Lenovo (Beijing) Limited**, Beijing (CN)

(72) Inventors: **Jianyang Chen**, Beijing (CN); **Shuang Li**, Beijing (CN)

(73) Assignee: **Lenovo (Beijing) Limited**, Beijing (CN)

(**) Term: **15 Years**

(21) Appl. No.: **35/519,388**

(22) Filed: **Jul. 14, 2023**

(80) **Hague Agreement Data**

Int. Filing Date: **Jul. 14, 2023**

Int. Reg. No.: **DM/233681**

Int. Reg. Date: **Jul. 14, 2023**

Int. Reg. Pub. Date: **Dec. 15, 2023**

(30) **Foreign Application Priority Data**

Jan. 17, 2023 (CN) 202330029297.4

(51) **LOC (15) Cl.** **14-02**

(52) **U.S. Cl.**

USPC **D14/314**

(58) **Field of Classification Search**

USPC D14/203.1–203.3, 300–302, 308, 341,
D14/348–349, 353–359, 361–363, 367,
D14/432–438, 496, 126, 386–388;
D13/103, 107–108, 158, 162–163, 184;
D10/40, 46, 106.1–106.3

CPC G06F 1/181; G06F 1/187

See application file for complete search history.

(74) Attorney, Agent, or Firm — SYNCODA LLC; Feng Ma

(57) **CLAIM**

The ornamental design for a computer mainframe as shown and described.

DESCRIPTION

1.1 : Front view

1.2 : Back view

1.3 : Left view

1.4 : Right view

1.5 : Top view

1.6 : Bottom view

1.7 : Top front right perspective view

1.8 : Top front right perspective view in an alternate configuration

(Continued)

The broken lines and any unshaded regions within the broken lines illustrate portions of the computer mainframe that form no part of the claimed design.
